UNITED STATES PATENT OFFICE.

GEORGE W. ANSLEY, OF LONG BEACH, CALIFORNIA.

WRENCH.

1,375,546.

Specification of Letters Patent. Patented Apr. 19, 1921.

Application filed June 10, 1920. Serial No. 388,012.

To all whom it may concern:

Be it known that I, GEORGE W. ANSLEY, a citizen of the United States, residing at Long Beach, in the county of Los Angeles and State of California, have invented certain new and useful Improvements in Wrenches; and I do hereby declare the following to be a full, clear, and exact description of the invention, such as will enable others skilled in the art to which it appertains to make and use the same, reference being had to the accompanying drawings, and to the letters and figures of reference marked thereon, which form a part of this specification.

The object of this invention is to provide a novel construction of plier wrench embodying a peculiar construction, whereby a rapid adjustment of the movable jaw, with reference to the stationary jaw, is possible; and embodying also a novel construction for extracting nails, and furthermore, an additional structure, making it possible to cut or break wire.

The invention has finally for its object certain refinements of structure and felicitous combination of parts going to make up the ultimate perfection of the wrench in its entirety, as will hereafter more fully appear in the specification.

An exemplary form of the invention is disclosed in the accompanying drawing, in which like reference characters designate corresponding parts throughout the several views.

Briefly described:

Figure 1 is a view in front elevation, partly in section, of the wrench.

Fig. 2 is a similar view, showing the wrench used to cut or break wire.

Fig. 3 is a side view, partly in section.

Fig. 4 is a transverse sectional view through the contacting jaws and through the wire receiving openings.

Fig. 5 is a fragmentary detached detail view, in perspective, of the lever for actuating the movable jaw, and

Fig. 6 is a fragmentary detail view, in perspective, of the movable jaw carrying a rack.

Referring now in detail to the drawing:

1 and 2 designate the handles of the wrench, the former of which is preferably constructed integral with a head 3, carrying the stationary jaw 4. The handle 2 constitutes a lever which is fulcrumed, toward one

end thereof, on a pin 5 passing through the head 3 and through a longitudinally extending slot 6 in said lever.

The extremity of the lever 2, adjacent the fulcrumed end thereof, is formed with teeth 7, engageable with rack teeth 8 of a rack bar 9, slidable transversely of the stationary jaw 4 and the movable jaw 10 preferably made integral with said rack bar 9.

The lever 2, between the fulcrum pin 5 and the teeth 7, is provided on opposite faces with transversely extending grooves 11, 11, shown most clearly in the detail view in Fig. 5.

A pin 12 is carried by the head 3, and a similar pin 13 is carried by a plate 14, disposed under one face of the head 3 and the corresponding face of the rack bar 9. When the lever 2 is moved in a direction away from the stationary handle 1, one of the grooves, in this instance the groove 11, shown in full lines in Fig. 1, engages one of the pins, which pin, in the position of the lever 2 as shown in Fig. 1, is the pin 13. Should the position of the lever 2 be reversed, the other groove 11 will, in the movement of said lever, engage the other pin 12, as is obvious. It will thus be seen that the lever 2 is reversible and may be used in either one of two positions with equal efficiency to suit the requirement of the particular operator, who may desire to use the wrench having the handles 2 and 1 convergently curved, or curved away from each other.

The head 3 is, of course, appropriately provided with a recess 15 for the reception of the corresponding end of the lever 2. The bottom of said recess 15, toward one end thereof, is transversely broached, as shown at 16, for the reception of the rack bar 9.

The rack bar 9 is longitudinally grooved, as shown at 17, in which engages the transversely extending rib or shoulder 18, extending along one longitudinal side of the groove 16.

The base of the movable jaw 4 is undercut, so as to provide a lip 19 overlying the corresponding edge of the rack bar 9, as shown clearly in Fig. 1. The movable and stationary jaws 4 and 10 are provided, on adjacent faces thereof, with transversely extending cross-sectionally arcuate grooves 20, 20 forming, when the jaws are in contact, as shown in Fig. 1, a transversely extending recess, extending across said jaws,

for the reception of the nail which it is desired to extract from an object, such as a box.

The jaw 3 and the plate 14 are provided with registering slots 21, 21, whereby a wire A may be passed therethrough, as shown in Fig. 2, and severed by actuation of the lever 2 to throw the rack bar 9, so as to bind the portion of the wire A projecting through said slot by one of the teeth of the rack bar.

The plate 14 and the head 3 are notched at corresponding points on one edge thereof, as shown at 22, 22, so that a second wire B may be disposed in said registering cutaway portions and be grasped by the end tooth of the rack bar 9, so that by moving said rack bar to cause said end tooth to move toward the head 3, the wire B may be severed.

It will be seen that by moving the lever 2 toward the handle 1, so that the pins 12 and 13 are disengaged from the grooves 11, 11, said lever may be pulled longitudinally to disengage the teeth 16 of the lever from the teeth of the rack bar, whereupon the rack bar, with its movable jaw, may be withdrawn for the purpose of inserting a rack bar carrying a larger jaw, or for any other purpose. In such longitudinal movement of the lever 2, the pin 5 slides in the slot 6 of the lever.

What I claim to be new is:

1. A wrench comprising a stationary jaw and a movable jaw, the latter carrying a rack bar, a handle carrying a head formed integral with said stationary jaw, and a lever having a toothed end engaging the

teeth of said rack bar and provided with a longitudinally extending slot, and a fulcrum pin carried by said head and passing through said slot.

2. A wrench comprising a handle having a head, a stationary jaw integral with said head, a movable jaw carrying a rack bar, and a lever having a toothed end engaging the teeth of said rack bar and fulcrumed on said head, and provided with transversely extending grooves on opposite faces thereof, and pins carried by said head, one of said pins being engageable with one of said transversely extending grooves in the movement of said lever, and the other of said pins being engageable with the other of said grooves when said lever is reversed.

3. A wrench comprising a handle having a head, a stationary jaw integral with said head, a movable jaw carrying a rack bar, and a lever having a toothed end engaging the teeth of said rack bar and fulcrumed on said head, and provided with transversely extending grooves on opposite faces thereof, and pins carried by said head, one of said pins being engageable with one of said transversely extending grooves in the movement of said lever, and the other of said pins being engageable with the other of said grooves when said lever is reversed, said lever being provided with a longitudinally extending slot, and a fulcrum pin carried by said head and passing through said slot.

In testimony whereof I hereunto affix my signature.

GEORGE W. ANSLEY.
